UNITED STATES PATENT OFFICE.

GEORGE W. ZERN AND MYRON H. MILHONE, OF GOOD HOPE, ILLINOIS.

CAR-MOVER.

SPECIFICATION forming part of Letters Patent No. 593,632, dated November 16, 1897.

Application filed May 17, 1897. Serial No. 636,952. (No model.)

To all whom it may concern:

Be it known that we, GEORGE W. ZERN and MYRON H. MILHONE, citizens of the United States, residing at Good Hope, in the county of

5 McDonough and State of Illinois, have invented a new and useful Car-Mover, of which the following is a specification.

The invention relates to improvements in car-movers.

10 The object of the present invention is to improve the construction of car-movers, and to provide a simple, inexpensive, and efficient device adapted to be readily applied to a wheel of a railway-car and capable of rotating the same in either direction for moving the car from or toward the operator.

15 The invention consists in the construction and novel combination and arrangement of parts, as hereinafter fully described, illustrated in the accompanying drawings, and pointed out in the claims hereto appended.

20 In the drawings, Figure 1 is a side elevation of a car-mover constructed in accordance with this invention and shown applied to a car-wheel. Fig. 2 is a perspective view of the device detached, showing the opposite side thereof.

25 Like numerals of reference designate corresponding parts in both figures of the drawings.

30 1 designates an operating-lever provided at one end with a curved bearing-plate 2, adapted to fit against and fulcrum the lever on the axle 3 of a car-wheel 4, which is engaged by a pivoted lever 5, fulcrumed on the operating-lever adjacent to the bearing end thereof. The operating-lever is maintained in engagement with the car-axle by a pivoted hook 6 and is adapted to bear against the 35 upper or lower face of the said axle for a purpose hereinafter described. The shank of the hook 6 is provided with an eye to receive a pivot 7, and the swing of the hook is limited by a keeper 8, forming opposite stops.

40 45 The wheel-engaging lever 5, which is pivoted between its ends, is angular and has one arm arranged at an angle to the other, as shown. The engaging arm is provided at its outer end with a hook 9 to receive the flange 50 of the wheel, and the other arm of the wheel-

engaging lever 5 is connected with the operating-lever by a spiral spring 10, which holds the hook 9 in engagement with the flange of the car-wheel.

The car-mover is adapted to engage a wheel 55 and its axle, as illustrated in Fig. 1 of the accompanying drawings, with the bearing end of the operating-lever resting upon the axle and the hook 9 engaging the wheel below the center thereof. By swinging the handle end 60 of the operating-lever upward the car-wheel is rotated forward and the car is moved from the operator; but the lever 5 and the operating-lever are adapted to be reversed and engage, respectively, the upper portion of the 65 car-wheel and the lower face of the axle, so that the operating-lever may be swung downward for moving the car-wheel in the direction of the operator.

70 It will be seen that the device is exceedingly simple and inexpensive in construction, that it is strong and durable, and that it may be readily engaged with a car-wheel. It will also be apparent that the device is adapted to engage a car-wheel at the top or bottom 75 and move the same in either direction.

What we claim is—

1. A car-mover comprising an operating-lever designed to be fulcrumed on an axle, a pivoted hook mounted on the operating-lever 80 and arranged to engage the axle at the opposite side thereof, and a spring-actuated hook carried by the operating-lever and arranged to engage the rim of the wheel, substantially as described. 85

2. A car-mover comprising an operating-lever adapted to be fulcrumed on an axle, a wheel-engaging lever pivoted between its ends to the operating-lever and provided at one end with a hook for engaging the flange 90 of a car-wheel, and a spiral spring connected with the other end of the same and with the operating-lever whereby the hook is held in engagement with a wheel, substantially as described. 95

3. A car-mover comprising an operating-lever provided at one end with a curved bearing-plate, a hook pivoted to the operating-lever, a keeper receiving the shank of the hook and limiting the swing of the latter, a 100

wheel-engaging lever pivoted between its ends on the operating-lever and having its arms arranged at an angle, one of the arms being provided with a hook and a spring connected with the other arm and with the operating-lever, substantially as described.

In testimony that we claim the foregoing as

our own we have hereto affixed our signatures in the presence of two witnesses.

GEORGE W. ZERN.
MYRON H. MILHONE.
